UNITED STATES PATENT OFFICE.

A. I. REEVES, OF HELENA, MONTANA.

VACUUM CLEANING-NOZZLE FOR PIANOS.

1,070,630.

Specification of Letters Patent. Patented Aug. 19, 1913.

Application filed October 31, 1912. Serial No. 728,959.

To all whom it may concern:

Be it known that I, A. I. REEVES, a citizen of the United States, residing at Helena, in the county of Lewis and Clark, State of 5 Montana, have invented certain new and useful Improvements in Vacuum Cleaning-Nozzles for Pianos; and I do hereby declare the following to be a full, clear, and exact description of the invention, such as will enable others skilled in the art to which it 10 pertains to make and use the same.

This invention relates to improvements in cleaners for pianos, organs or the like, and has particular reference to vacuum 15 cleaner suction nozzles particularly adapted therefor.

The principal object of the invention is to provide a simple and efficient device of this character by means of which small spaces 20 and corners of the instruments may be readily and thoroughly cleaned without danger of marring or scratching the polished parts.

Other objects and advantages will be apparent from the following description, when 25 taken in connection with the accompanying drawings.

In the drawings: Figure 1 is a sectional detail of a portion of a piano showing the manner in which my cleaning nozzle is capable of removing dust from beneath the 30 music rack. Fig. 2 is an enlarged elevation of the nozzle. Fig. 3 is a vertical longitudinal sectional view through the nozzle. Fig. 4 is an end view.

Referring particularly to the accompanying drawings 10 represents a rubber hose which is suitable to be connected to any well-known type of suction device. The suction 35 device is omitted as the same forms no part 40 of my invention. On one end of the hose 10 and projecting a suitable distance beyond said end is a ring of bristles 11. A suitable covering 12 of soft material, as rubber, leather or the like, is secured at one end by 45 means of fine cords 13, these cords tightly

clamping the covering to the hose. The other end of the covering embraces the inner ends of the bristles 11, and is tightly secured by means of a cord 14.

In the ordinary use of the nozzle, suction 50 being produced in the pipe 10, said nozzle is passed over the dusty surface so that the bristles 11 will disturb the dust, the dust then being sucked up through the pipe 10.

When it is desired to get into a small and 55 narrow space, the ring of bristles may be readily pinched together so that they will easily enter the space. This is very advantageous in cleaning the corners of any large musical instruments, as pianos, organs or the 60 like, as the bristles 11 may be easily pinched into a small space and loosen the dust therein.

A great majority of nozzles used with 65 vacuum cleaning devices heretofore, are stiff and rigid, metallic means being provided for holding the bristles, which scratch or mar the polish of the musical instrument. It will therefore be readily seen that applicant 70 has advanced a step in the production of 75 vacuum suction nozzles, in that the present device can be used on costly polished surfaces without danger to the surfaces, and that the device can readily be gotten into much smaller spaces than that capable of 75 being reached by metal nozzles heretofore.

What is claimed is:

In a suction nozzle, a flexible rubber pipe, a ring of bristles disposed around one end of the pipe and projecting therebeyond and a 80 fabric covering secured to the pipe and bound around and holding the bristles on said pipe.

In testimony whereof, I affix my signature, in the presence of two witnesses.

A. I. REEVES.
